UNITED STATES PATENT OFFICE.

FREDERICK E. LAWRENCE AND EMORY A. GREEN, OF SANTA ROSA, CALIFORNIA.

FURRING STRIP.

Application filed April 17, 1924. Serial No. 707,209.

This invention relates to furring strips as used in the plastering of walls, especially the outer walls of stucco houses wherein the plaster is carried on wire mesh or the like.

5 In the construction of such houses it has been common practice to nail wooden strips over the wall to be plastered so as to provide the necessary furring means to hold the wire mesh properly spaced from the wall, the 10 wire mesh being usually nailed to the furring strips, or the wall and the strips.

When so used the strips have several disadvantages, amongst which are, the weakening of the plaster coating by reducing its 15 thickness at the position of the strips and of forming the nucleus of cracks in the plaster which may be caused by any of several adverse functioning of the strips in relation to the plaster.

20 The objects of our invention are to provide means which will dispense with the usual wooden furring strips and provide a wall of even thickness, not reduced in thickness at the furring lines, but strengthened at 25 these points by a special wire interlocked within the plaster, and also a furring strip which is easier to apply than a wooden strip, is lower in cost, which may be bent around arched windows and the like if desired, and 30 which will form in combination with the wire mesh stretched over it a yielding carrier for the plaster structure very little affected by the localized changes in the supporting wall, thereby preserving to a maximum 35 the original strength of the plaster coating and insuring its freedom from cracks.

We carry out our invention by providing 40 a wire furring strip which is interlocked by the plaster to form a reinforced unit with the regular mesh stretched over the furring wire.

The drawings hereto show our preferred 45 way of forming the wire furring strip and its relation to the regular mesh and stucco plaster.

Figure 1 is a short piece of my wire furring strip drawn approximately full size.

Figure 2 is an end view of Figure 1.

Figure 3 is a cross section of a building 50 wall showing our strip in place, the outer wire mesh stretched over it and the stucco wall outline dotted.

Figure 4 is a plan view of Figure 3.

In Figures 1 and 2 our wire furring strip 55 is seen to be simply a heavy wire (1) which has been given a spiral twist so that it will extend uniformly the distance "A" from any surface upon which it is laid, no matter how it is laid thereon.

The distance "A" represents the furring space desired and of course is made to meet the standards of construction, and the wires are ordinarily provided in lengths of about ten feet for convenience of application.

In applying our wire furring strips, they 65 are simply secured in place against the building wall (2) by nails or staples (3) applied at suitable intervals as shown in Figures 3 and 4.

70 After securing a sufficient number of the furring wire strips to the face of the building the usual wire mesh (4) is stretched over the strips and secured to the building either by suitable nails (5) adjacent the furring strips or elsewhere, and if desired also secured to the furring wires by a wire or other clip as indicated at (6).

75 After the wires are secured as indicated the plaster or cement stucco is applied and 80 finished to a surface beyond the wire mesh as indicated by the dotted section (7).

It is evident from what has been said that 85 the plaster readily finds its way in back of all the wires and interlocks the furring wires with the mesh wires to form a uniform reinforced mass without a point of weakness from which to start cracking.

90 It is evident that a great variety of kinds or bends could be impressed on the wire, or a single, double or triple wire could be used, and the end view of the formed strip can be circular, square, angular, triangular or any other form, and any such bending or forming of a wire or wires in order to provide a 95 nailing portion and a projecting portion to act as furring, or the use of any such wire or wires in the formation of a reinforced stuc-

co wall coming within the scope of this invention we intend to embrace in our appended claim.

We claim:—

5. A furring strip for a plaster wall comprising a wire formed into a spiral of a diameter equal to the furring distance, said spiral being of uniform diameter and adapt-

ed for securing at any point on the spiral to a wall to be plastered while presenting an outer side adapted for securing and uniformly spacing a plaster retaining lathing sheet.
